(57) **CLAIM**

The ornamental design for a wristband attachment device, as shown and described.

DESCRIPTION

FIG. 1 is a top side perspective view of my design for a wristband attachment device,

FIG. 2 is a back side perspective view thereof,

FIG. 3 is a front elevation view thereof,

FIG. 4 is a back elevation view thereof

FIG. 5 is a top plan view thereof,

FIG. 6 is a bottom plan view thereof,

FIG. 7 is a right view thereof; and,

FIG. 8 is a left view thereof.

In the drawings, the broken lines are for the purpose of illustrating environment only and form no part of the claimed design.
